CLAIM

The ornamental design for a dial top-housing panel for
telephone handset or similar article.

DESCRIPTION

FIG. 1 is a rear, top, and right side perspective view of
an operative dial top-housing panel for a handset tele-
phone or similar article showing my new design in full
lines with the broken line showing of environmental
association matter being for illustrative purposes only
and forming no part of the claimed design;

FIG. 2 is a left side elevational view of the dial top-
housing panel in full lines, and the environmental matter
shown in broken lines; and;

FIG. 3 is a front elevational view of the dial top-housing
panel shown in full lines and the environmental matter
shown in broken lines.
